(57) **CLAIM**

The ornamental design for a display screen with graphical user interface for a computer program product, as shown and described.

DESCRIPTION

FIG. 1 is a front view of a first image of a display screen with graphical user interface for a computer program product showing my new design;

FIG. 2 is a front view of a second image of a display screen with graphical user interface for a computer program product showing my new design;

FIG. 3 is a front view of a third image of a display screen with graphical user interface for a computer program product showing my new design;

FIG. 4 is a front view of a fourth image of a display screen with graphical user interface for a computer program product showing my new design; and,

FIG. 5 is a front view of a fifth image of a display screen with graphical user interface for a computer program product showing my new design.

The dot-dash broken lines illustrate a display screen or portion thereof and form no part of the claimed design. The broken line illustrate portions of the display screen with graphical user interface for a computer program product that form no part thereof. The appearance of the transitional image sequentially transitions between the images shown in FIGS. 1-5. The process or period in which one image transitions to another image forms no part of the claimed design.
